UNITED STATES PATENT OFFICE.

ERNST KÖPKE, OF HONOLULU, TERRITORY OF HAWAII, ASSIGNOR TO KOPKE CLARIFIER COMPANY, LIMITED, A CORPORATION OF THE TERRITORY OF HAWAII.

CENTRIFUGAL SEPARATOR.

1,119,173.

Specification of Letters Patent.

Patented Dec. 1, 1914.

Application filed December 8, 1911. Serial No. 664,593.

To all whom it may concern:

Be it known that I, ERNST KÖPKE, a citizen of the United States, residing at Honolulu, county of Honolulu, Territory of Hawaii, have invented certain new and useful Improvements in Centrifugal Separators; and I do hereby declare the following to be a full, clear, and exact description of the invention, such as will enable others skilled in the art to which it appertains to make and use the same.

This invention relates to centrifugal machines for clarifying solutions.

The object of the present invention is to provide means whereby the fine particles suspended in the fluid may be more perfectly separated therefrom prior to the discharge of the fluid from the rotating separator.

In the process of clarifying liquids in a centrifugal machine, it often happens that mechanical impurities in minute particles which have nearly the same specific gravity as the liquid, are carried off in the discharge. The current caused by the constant stream of fluid passing through the machine produces a disturbing force which prevents the quick separation of these particles from the liquid. If there were no current, the particles would be thrown either to the inner or to the outer surface of the liquid according as their specific gravity is less or is greater respectively than that of the liquid. This disturbing force of the current is inversely proportional to the area of the discharging stream.

The invention contemplates the introduction of an intervening screen to create a zone of comparatively quiet liquid back of the screen and just before the discharge of the fluid. This screen may consist of perforated plate, wire netting, cloth or other suitable materials, the size of the screen as well as the degree of its porosity being chosen such that an even passage of the fluid may be effected as nearly as possible through the entire screen. By the introduction of such an intervening screen, the finely divided particles in this zone are readily affected by the centrifugal force, and are therefore much more easily separated than heretofore where the discharging stream is of a higher velocity and not diffused. When these particles are lighter than the fluid they may pass on with the fluid unless the screen

is sufficiently fine to prevent their passage, in which case the screen becomes a strainer or filter. In my experiments I have not found a deposit on the intake side of the screen, but there may be cases where this is likely to take place. Such a deposit would tend to prevent the passage of the fluid through the screen. The direction of the flow of the fluid through the screen is preferably opposite to the direction of the centrifugal force, and such a deposit on the intake side of the screen could be removed by stopping the flow of liquid into the centrifugal and introducing clean water on the discharge side of the screen thereby removing the deposit and cleaning the screen. The dislodged impurities being lighter than the fluid escape from the zone back of the screen to a position under the skimming ring and are there held until discharged.

As my invention may be carried out in a great variety of ways, I do not wish to confine myself to any specific construction, and for this reason only a few of the simpler forms of the invention are illustrated in the accompanying drawings, forming a part of this specification, in which:

Figure 1 represents in sectional elevation a portion of a centrifugal separator, with the screen depending vertically from the in-turned flange at the top of the imperforate wall of the separator, and a horizontal skimming or deflecting ring attached to the lower edge of said screen. Fig. 2 is a view similar to Fig. 1, with an inclined or funnel shaped skimming or deflecting plate instead of the horizontal ring. Fig. 3 illustrates a funnel shaped combined screen and deflecting plate. Fig. 4 represents a horizontal screen attached to the wall of the separator. Fig. 5 illustrates the screen and the skimming or deflecting plate applied above the top of the centrifugal separator.

Referring to the drawings, 1 represents a portion of the rotatable imperforate cylindrical drum of the separator, provided at its upper edge with an in-turned flange 2. A short cylindrical ring 3, of perforated plate, wire mesh material or the like, and smaller in diameter than the drum 1, is attached to the flange 2, Figs. 1 and 2. Cloth, wire netting, or other medium 4, may either be attached to the ring 3 or simply be held inside of said ring by centrifugal force. In Fig. 1, an annular plate 5 is secured to the

lower edge of the ring 3, in a practically horizontal position, for deflecting the rising fluid and causing same to flow outside of and then through the perforations in the 5 ring 3 and through the medium 4, which form the intervening screen, before being discharged over the edge of the flange 2.

In Fig. 2, the skimming or deflecting plate 6 is inclined to the horizontal, and is the 10 frustum of a hollow cone or funnel shaped, with its upper rim 7 attached to the under- side of the flange 2 between the ring 3 and the drum 1. This plate 6 is joined to the 15 lower edge of the ring 3 near the middle of said plate, as shown. A series of holes 8 are provided in the plate 6 near its upper rim 7 for the passage of the fluid to and then through the screen. If desired, of course the upper rim 7 of this plate 6 could be cut 20 away in lieu of the holes 8. When the in- turned flange 2 is wide, holes 9 may be made in same just inside of the screen, as shown. The plates 5 and 6 prevent the fluid from 25 rising inside of the screen.

25 In Fig. 3, the screen 10 is funnel shaped and is secured below the flange 2. Its lower portion 11 is made imperforate and has the same function as the plate 5 shown in Fig. 1.

In Fig. 4, the screen 12 is horizontal and 30 is attached to the wall of the drum 1. If desired, the annular inner portion 13 may be made imperforate, as shown.

In Fig. 5, the ring 3 is secured upon the 35 top of the flange 2, and a funnel shaped deflecting plate 14 is provided outside of the ring 3, as shown. Holes 15 are made in the flange 2 between the lower edges of the plate 14 and the ring 3 respectively. In this case, the fluid in rising passes through the holes 40 15 and is deflected by the plate 14 and then

passes through the perforations in the ring 3 and through the medium 4 and is discharged over the top of this screen.

I claim:

1. A centrifugal separator having a rotor 45 providing a cylindrical unobstructed stratifying chamber from which material is discharged axially, and means for preventing the disturbance of the established strata by cross currents converging to the discharge 50 opening, comprising a screen-like partition within the rotor in the path of the outflow therefrom and adjacent the discharge opening, whereby the discharge is broken up into a multitude of small streams and spread 55 over considerable area.

2. A centrifugal separator having a rotor providing a cylindrical unobstructed stratifying chamber from which material is discharged axially, means for introducing the 60 material to be separated into said chamber as a substantially tubular axially moving body of fluid which has previously attained substantially the angular velocity of the centrifugal apparatus, and means for preventing 65 the disturbance of the established strata by cross currents converging to the discharge opening, comprising a screen-like partition within the rotor in the path of the outflow therefrom and adjacent the discharge 70 opening, whereby the discharge is broken up into a multitude of small streams and spread over considerable area.

In testimony whereof I affix my signature, in presence of two witnesses.

ERNST KÖPKE.
